UNITED STATES PATENT OFFICE.

KENNETH J. UNWIN, OF SHREWSBURY, MASSACHUSETTS, ASSIGNOR TO CROMPTON & KNOWLES LOOM WORKS, OF WORCESTER, MASSACHUSETTS, A CORPORATION OF MASSACHUSETTS.

WEIGHT-CONTROLLED DETECTOR FOR LOOMS.

Application filed January 5, 1926. Serial No. 79,437.

This invention relates to improvements in multiple needle weft detectors for looms and it is the general object of the invention to render detectors of this type less likely to abrade fine yarn than detectors at present in use without sacrificing precision of indication.

Detectors of the multiple needle type employ a plurality of needle or wire detectors usually located in a plane and cooperating with spirally arranged holes in the bobbin. As heretofore made the detector needles have been subject to pressure either by springs or weights at the time they were engaged by the bobbin and where the yarn is fine and the bobbin is active for a comparatively long time the needles abrade the yarn to an objectionable degree. It is a further object of my invention to return the needle detectors to normal position after each detecting operation but to remove pressure from the needles prior to engagement with the yarn.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a side elevation of a detector showing the same in the position it occupies immediately before engagement of the detectors with a full bobbin, certain parts being in section.

Fig. 2 is a horizontal section on line 2—2 of Fig. 1, and

Figs. 3 and 4 are vertical sections on lines 3—3 and 4—4 of Fig. 1, respectively.

Referring to the drawings it will be seen that I have provided a stand 10 to which is secured a support 11 by means of bolt 12. Said support is provided with a rib 13 which enters a notch 14 in the lower end of a needle carrier 15. Said carrier has a rearwardly extending portion 16 and an upwardly extending portion 17 through which extend, respectively, the lower yarn engaging and upper indicating portions 18 and 19 of the needle detectors 20. The carrier 15 is provided with spaced ears 21 and 22 which

form bearings for a pin 23 on which is pivotally mounted a detector withdrawing device 24 having depending spaced arms 25 and 26, respectively, between which extends rod 27. Said rod projects behind all of the detectors 20 and when said withdrawing device is moved forwardly by some portion of the transerrer mechanism not shown, coming in contact with a wing 28 said rod moves all of the detectors forwardly out of the path of the incoming bobbin.

An actuating lever 29 is normally located above the indicating ends 19 of the detectors and is given a downward movement when the bobbin B carried in the shuttle S is in the extreme forward position on each detecting beat of the loom. When yarn is present all of the detectors are moved forwardly and said actuating lever moves downwardly without interruption but when one of the openings 30 of the bobbin B is uncovered the corresponding detector 20 will remain in rearward position and downward movement of the actuating lever is thereby prevented to give indication of weft exhaustion and effect a change in the operation of the loom. Tension spring 31 is suspended between the forwardly extending end of a bracket 32 secured to the carrier 15 and a pin 33 held by the tension of the spring against the rear face of the support 11. The spring affords a yielding means to hold the detector in normal position but permits the carrier 15 to move forwardly when engaged by an improperly placed bobbin. The matter thus far described is of common construction and forms no part of my invention.

Heretofore it has been usual to provide some device for holding the detectors 20 in rearward position and these devices have comprised either a single spring device held in contact with all of the detectors or individual weights, one for each detector, depending upon the class of work to be done by the detectors. Of these two means for returning the detectors the spring device is somewhat more sensitive because of the fact that on an indicating beat of the loom the non-indicating detectors move forwardly and carry the spring device away from the detecting needle and the latter is held in rear

position merely by its weight and the friction against sliding in carrier 15. In such a device, however, where the yarn is fine the detectors are found to abrade the yarn because of the pressure of the spring device and my invention relates to a device for returning all of the detectors to normal position after each detecting beat of the loom, so arranged that the means is moved out of engagement with the detectors prior to contact of the yarn and detectors. In this way the yarn is not subjected to the pressure present in that form of detector which employs the spring device or weights.

15 In carrying out my invention I pivot a weight 50 on the pin 23 and provide said weight with an arm 51 positioned for engagement with the intermediate portion 52 of a U-shaped controller 53. Said controller 20 53 is provided with a pair of parallel legs on the rear end of each of which is adjustably mounted a nut 54 positioned for engagement with a bunter 55 on the binder A on the lay L. The carrier 15 is provided 25 with upwardly extending lugs 56 which are recessed as at 57 to form guides for the legs of the controller 53. The weight 50 is mounted for free pivotal motion on the pin 23 and the connecting portion 52 lies in front 30 of the upright portions of the detectors 20.

In operation as the lay moves forwardly the bunter on the binder will engage the nuts 54 and the controller will be moved forwardly to move the connecting portion 35 52 thereof away from the upright portions of the detectors, this motion also moving the weight 50 forwardly from the full line to the dotted line position shown in Fig. 1. The bobbin then engages the detectors, 40 which exert very little pressure on the yarn because of the fact that the weight is moved away from the detectors. As the lay recedes the weight 50 will return the controller to the rear position indicated in Figs. 1 and 2. 45 and inasmuch as the connecting portion 52 extends in front of the detectors the latter will also be returned to their normal full line position shown in Fig. 1.

From the foregoing it will be seen that I 50 have provided a weft detector returned to operative position by a device which is moved out of operative relationship with the detector prior to engagement of the latter with the yarn to be detected so that the detectors may exert a minimum of pressure 55 against the yarn.

Having thus described the invention it will be apparent that changes and modifications may be made therein by those skilled 60 in the art without departing from the spirit and scope of the invention, and I do not wish to be limited to the details herein disclosed, but what I claim is:

65 1. In a weft detector for looms, a detecting element having a movement which it de-

rives from the moving yarn to be detected, means to return the detector to normal detecting position, and mechanism other than the detector to move said means out of operative relationship with the detector member prior to engagement of the latter with the yarn to be detected. 70

2. In a weft detector for looms, a detector element having a movement which it derives from the moving surface to be detected, 75 means to return the detector to normal detecting position, and mechanism operating independently of the detector to move said means out of operative relationship with the detector prior to engagement of the latter 80 with the surface to be detected.

3. In a weft detector for looms, a lay, a detector mounted for longitudinal movement to be engaged by the surface to be detected, means to return the detector to normal position after a detecting movement, and controlling mechanism independent of the detector having a portion interposed between the means and the detector, said mechanism to be engaged by the lay to move the means away from the detector on a forward movement of the lay, said controller being returned on the backward stroke of the lay by the means and said portion returning the detector to normal detecting position. 90 95

4. In a weft detector for looms, a lay, a plurality of longitudinally movable detectors movable forwardly with the surface to be detected, means to return said detectors to normal detecting position after a detecting movement, and mechanism engaged by the lay and independent of the detectors and having a portion thereof located between the detectors and the means, whereby said means is moved away from the detectors on the forward movement of the lay and said detectors are moved to normal position on the rearward movement of the lay. 100 105

5. In a weft detector for looms, a lay, a plurality of longitudinally movable detectors positioned for engagement with the surface to be detected, a U-shaped controller to be engaged by the lay and having a portion thereof located in front of the detectors, and means normally acting on the controller to move the same rearwardly, the lay engaging the controller on the forward movement thereof to move the detectors and controller forwardly independent of the detectors and prior to engagement of the latter with the surface to be detected, said means and controller acting on the backward stroke of the lay to return the detectors to normal detecting position. 115 120 125

6. In a weft detector for looms, a lay, a plurality of longitudinally slidable detectors positioned to engage the surface to be detected, a carrier for said detectors, a weight freely pivoted on said carrier, and a U- 130

shaped controller guided on said carrier and positioned for engagement with the lay to move said weight forwardly prior to engagement of the detectors with the surface to be detected, the intermediate portion of the U-shaped controller extending between the detectors and the weight whereby upon

backward movement of the lay the weight and controller will return the detectors to normal detecting position.
